UNITED STATES PATENT OFFICE.

WILLIAM A. NEELY, OF LYNN, MASSACHUSETTS.

DESIGN FOR A SHOE.

SPECIFICATION forming part of Design No. 28,147, dated January 11, 1898.

Application filed October 18, 1897. Serial No. 655,627. Term of patent 14 years.

To all whom it may concern:

Be it known that I, WILLIAM A. NEELY, a citizen of the United States, residing at Lynn, in the county of Essex and State of Massachusetts, have invented and produced a new and useful Design for a Shoe, of which the following is a description, reference being had to the accompanying drawings, forming a part thereof.

10 Figure 1 is a front perspective view of a shoe illustrating my design, and Fig. 2 is a side elevation of the shoe shown in Fig. 1.

The leading feature of my design consists in lines of double beading arranged at each 15 side of and substantially in parallelism with the edges of the front opening of the upper, on the quarters and extending around the heel portion of the upper, simulating foxing, and across the toe portion of the vamp to simulate a separate tip, the beading consisting of 20 two rounded parallel ribs with an intermediate connecting narrow flat surface.

In the drawings a line of the ornamental beading *a* is disposed along the upper at each 25 side of and substantially in parallelism with the edges of the front opening of the upper,

presenting to the eye the appearance of a side stay at each side of the opening, having an ornamental edge finish. A line *b* of the beading is also shown as arranged along the quarters, starting from the point *b'* and inclining upwardly and rearwardly and extended around the heel portion, thus presenting to the eye the appearance of foxing. I have also shown a line *c* of the beading arranged transversely across the toe portion of the vamp and thereby giving the similitude of a separate tip. 30

35 My design comprises a shoe having the double beading applied at all of the points described, as well as at any of them.

Having fully described my invention, what I claim, and desire to secure by Letters Patent, is—

The design for a shoe, substantially as herein shown and described. 40

45 In testimony whereof I have signed my name to this specification in the presence of two subscribing witnesses.

WILLIAM A. NEELY.
